DESIGN FOR A TOOTHPICK CASE

Timothy L. Keough, Roxbury, Mass.

Application July 2, 1934, Serial No. 52,433

Term of patent 3½ years

To all whom it may concern:

Be it known that I, TIMOTHY L. KEOUGH, a citizen of the United States, residing at Roxbury, in the county of Suffolk and State of Massachusetts, have invented a new, original, and ornamental Design for a Tooth Pick Case, of which the following is a specification, reference being had to the accompanying drawing, forming part thereof.

Figure 1 is a view in front elevation of a tooth pick case, showing my new design.

Figure 2 is a view in rear elevation thereof.

Figure 3 is a top plan view.

I claim:

The ornamental design for a tooth pick case, as shown.

TIMOTHY LAWRENCE KEOUGH.
